AWNING

Robert E. Butler, La Crosse, Wis.

Application July 12, 1955, Serial No. 36,926

Term of patent 14 years

(Cl. D21—6)

Figure 1 is a perspective view of an awning, showing my new design;

Figure 2 is a side elevational view thereof, the opposite side having substantially the same appearance;

Figure 3 is a bottom plan view thereof; and

Figure 4 is a cross-sectional view thereof, taken on line 4—4 of Figure 3.

Portions of the drawing figures are diagonally lined to indicate translucency.

I claim:

The ornamental design for an awning, as shown and described.
